CLAIM

The ornamental design for a child's tricycle, as shown and described.

DESCRIPTION

FIG. 1 is a perspective view of the child's tricycle of the present invention showing my new design. The broken-line showing of the pedals, handle bar, chain and sprocket, and reflector is for illustrative purposes only, and forms no part of the claimed design;

FIG. 2 is a side elevational view of the left side of the child's tricycle of FIG. 1;

FIG. 3 is a side elevational view of the right side of the child's tricycle of FIG. 1;

FIG. 4 is a front elevational view of the child's tricycle of FIG. 1;

FIG. 5 is a rear elevational view of the child's tricycle of FIG. 1;

FIG. 6 is a top plan view of the child's tricycle of FIG. 1; and, FIG. 7 is a bottom plan view of the child's tricycle of FIG. 1.
